UNITED STATES PATENT OFFICE.

AUGUST SCHMIDT, JR., OF SCHENECTADY, NEW YORK, ASSIGNOR TO GENERAL ELECTRIC COMPANY, A CORPORATION OF NEW YORK.

SIGNALING SYSTEM.

Application filed July 3, 1923. Serial No. 649,371.

To all whom it may concern:

Be it known that I, AUGUST SCHMIDT, Jr., a citizen of the United States, residing at Schenectady, county of Schenectady, State 5 of New York, have invented certain new and useful Improvements in Signaling Systems, of which the following is a specification.

My present invention relates to signal 10 transmitting systems, and more particularly to systems in which an electron discharge device is employed for the production of high frequency oscillations.

The object of my invention is to provide 15 a simple and efficient system for controlling the amplitude of the high frequency oscillations in accordance with desired signals.

The novel features which I believe to be 20 characteristic of my invention are set forth 25 with particularity in the appended claims. My invention itself, however, both as to its organization and method of operation will best be understood by reference to the following description taken in connection with 25 the accompanying drawing in which I have shown diagrammatically one way whereby my invention may be carried into effect.

I have indicated in the drawing an electron discharge device 1 of the usual three 30 electrode type which is connected to produce oscillations and supply them to the antenna 2 by means of the coupling transformer 3. The oscillating circuit of device 1 comprises 35 an inductance 4 and parallel capacity 5 connected between the grid 6 and plate 7 of the device 1. Current for the operation of device 1 is supplied to the plate circuit from a direct current source 8, the positive terminal 40 of which is connected to the plate 7 through a high frequency choke 9 and the negative terminal of which is connected to the cathode 10 through the plate circuit of a second 45 three-electrode electron discharge device 11. The oscillating system of the device 1 also includes a connection from the cathode 10 to an intermediate point 12 in the inductance 4. Stopping condensers 13 prevent the flow of direct current in the oscillating circuit.

The cathode 10 of device 1 and the cathode 50 14 of device 11 are heated by means of alternating current supplied by transformers 15 and 16. The effect of the alternating current employed for heating the cathodes 55 in varying the amplitude of the oscillations

produced is eliminated by bringing the connections from the plates and grids to the cathodes to points 17 and 18 intermediate the terminals of the transformer secondaries in the well known manner. The same effect is secured in the case of the oscillating circuit of device 1 by making the connection from point 12 to a point 19, which is intermediate the two condensers 20, which are connected in series across the terminals 60 of cathode 10.

The grid circuit of device 11 includes a condenser 21 in shunt to which is connected a source of potential 22 and a key 23. The grid of device 1 is connected to the negative 70 terminal of source 8 through a high frequency choke 24 and a resistance 25 and thereby given a normal negative bias of the value desired for the efficient production of 75 oscillations.

It will be noted that current supplied to the plate circuit of device 1 has to pass through device 11. When key 23 is closed the grid of device 11 is made positive by source 22 so that the resistance of device 11 80 becomes comparatively low and device 1 delivers oscillations with full power to antenna 2. When key 23 is opened the grid of device 11 becomes negatively charged by 85 reason of grid condenser 21 and the resistance of device 11 in the plate circuit of device 1 is thereby enormously increased. The current delivered to the oscillator will be greatly decreased and at the same time the grid of device 1 will become so strongly 90 negative by reason of its connection to the negative terminal of source 8 that the production of oscillations will be entirely interrupted or their amplitude reduced to a very 95 small percentage of their maximum amplitude.

When key 23 is again closed the grid of device 11 becomes positive again permitting maximum current to be supplied to the oscillator and the grid of device 1 also becomes 100 much less negative permitting the production of oscillations of maximum amplitude. It will be observed that while very high voltages may be employed in the system described, the control is effected entirely in a 105 circuit of very low voltage and small power and there are no moving parts required which carry large currents. The actions described also occur practically instantaneously so that it is possible to transmit signals at 110

high speed by substituting a moving tape control for the key 23 if desired.

While I have shown and described the preferred embodiment of my invention it will be apparent that my invention is not limited to the particular embodiment shown but that many modifications in the circuit arrangements and instrumentalities employed in carrying out my invention may be made without departing from the scope thereof as set forth in the appended claims.

What I claim as new and desire to secure by Letters Patent of the United States, is:—

1. The combination in a high frequency 15 signaling system of an electron discharge device, circuit connections for said device whereby it is adapted to produce high frequency oscillations, a second electron discharge device connected in circuit with said 20 first device in such a way that current is supplied to the first device through the second device, and means for varying the resistance of the second device substantially 25 instantaneously from a low value to a much greater value, and simultaneously producing a large increase in the resistance of the first device.

2. The combination in a high frequency 30 signaling system of an electron discharge device having a cathode, an anode and a controlling grid, circuit connections for said device whereby it is adapted to produce high frequency oscillations, a second similar electron discharge device connected in circuit 35 with said first device in such a way that current is supplied to the first device through the second device, and means for varying the resistance of the second device substantially instantaneously from a low value to a much 40 greater value and simultaneously increasing the negative potential upon the grid of the first device.

3. The combination in a high frequency 45 signaling system of an electron discharge device having a cathode, an anode and a controlling grid, a second similar electron discharge device connected in circuit with said

first device in such a way that current is supplied to the first device through the second device and means for varying the 50 potential of the grid of the second device substantially instantaneously from a negative value sufficient to substantially interrupt the flow of current therethrough to a positive value high enough to permit maximum current to flow therethrough and simultaneously increasing the negative potential 55 upon the grid of the first device.

4. The combination in a high frequency 60 signaling system of an electron discharge device having a cathode, an anode and a controlling grid, circuit connections for said device whereby it is adapted to produce high frequency oscillations, a source of direct current having its positive terminal connected 65 to the anode of said device and its negative terminal connected to the cathode of a second similar device, a connection from the anode of the second device to the cathode of the first device, a connection from the 70 grid of the first device to the negative terminal of said source, and means for substantially instantaneously varying the potential of the grid of the second device from a negative value sufficient to substantially 75 interrupt the flow of current therethrough to a positive value high enough to permit maximum current to flow therethrough.

5. The method of operating an electron 80 discharge device having an electron emitting cathode, an anode and a controlling grid with circuit connections connected thereto for the production of high frequency oscillations which consists in supplying current thereto through a resistance device, varying the value of the resistance of said device between a low and a comparatively high value, and simultaneously producing a high negative potential on the grid of the electron 85 discharge device.

In witness whereof, I have hereunto set my hand this second day of July, 1923.

AUGUST SCHMIDT, JR.
